UNITED STATES PATENT OFFICE.

JOSEPH A. GOODWIN, OF MILLVILLE, NEW JERSEY.

MONOPLANE.

1,025,085.

Specification of Letters Patent. Patented Apr. 30, 1912

Application filed December 3, 1910. Serial No. 595,405.

To all whom it may concern:

Be it known that I, JOSEPH A. GOODWIN, a citizen of the United States, residing at Millville, in the county of Cumberland and State of New Jersey, have invented new and useful Improvements in Monoplanes, of which the following is a specification.

This invention relates to heavier-than-air flying machines, and particularly to flying machines of the monoplane type.

The primary object of the invention is to provide a monoplane machine having means for securing and maintaining complete automatic lateral stability in any wind not exceeding in velocity the speed of the machine.

A further object of the invention is to provide automatically balancing supporting surfaces having a normal bird-like flutter or vibratory action operating to increase the speed and stability of the machine.

A still further object of the invention is to provide a monoplane of maximum strength, and in which the balancing action may be regulated to suit the weight of the load and to make the machine as stiff or flexible as occasion may demand.

The invention consists of the features of construction, combination and arrangement 30 of parts, hereinafter fully described and claimed, reference being had to the accompanying drawings, in which:—

Figure 1 is a front elevation of the body 35 of a flying machine embodying my invention, showing in full lines the normal and in dotted lines one of the abnormal positions of the wings. Fig. 2 is a top plan view of the same. Fig. 3 is a bottom plan view. Fig. 4 is an end elevation. Fig. 5 is a section on the line 5—5 of Fig. 2.

In the embodiment of my invention in an organized machine any suitable type of fuselage, wheel or skid base and propelling and steering means may be employed, the 45 invention residing strictly in the construction of the body of the machine, *i. e.*, the supporting surfaces and means for controlling the same to balance the machine.

Referring to the drawings, 1 designates 50 a central plane or supporting surface, from the side edges of which rise upright vanes or surfaces 2, to the upper edges of which are connected the inner edges of the transverse or lateral supporting surfaces or wings 3, each of which portions is composed as

usual of a frame of wood or other suitable material having a fabric covering.

The plane or surface 1 is preferably curved from front to rear, parabolically or otherwise, for the dynamical reactions of 60 the air thereon, and the lateral supporting surfaces or wings 3 are similarly curved from front to rear or in a direction transversely of their length to increase their lifting action. The rear portions of these 65 wings are curved or inclined inwardly and rearwardly behind the rear longitudinal frame bars thereof to provide resilient tail extensions 4, which provide for the escape of any excess quantity of air from beneath 70 the wings and at the same time impart to the wings the general shape of a bird's 75 wings, whereby the sustaining effect of the wings is promoted. The upright surfaces 2 may extend vertically, but preferably di- 80 verge or incline upwardly and outwardly between their bottom and top edges, so as to dispose them at a dihedral angle for a bearing action on the air, by which said surfaces are caused to have a balancing effect in a well-known way when the machine tilts in either direction. Such surfaces also 85 operate in the nature of parallel keels to prevent lateral displacement or skidding of the machine from its course of travel.

The wings or transverse supporting surfaces 3 are hinged or pivoted at their inner edges, as indicated at 5, to the upper edges of the surfaces 3, to render said wings flexible, that is, to adapt said wings to swing in a vertical plane. As shown, said wings normally incline upwardly and outwardly at an angle, preferably a minimum dihedral working angle, and are movable upwardly 90 from such position under excess air pressure to any dihedral angle position between such minimum dihedral angle and the maximum angle at which the wings may lie without impairing their sustaining and stabilizing action.

Fixed to the frame bars of the surface 1 or surfaces 2 and extending upwardly in the space between the latter to a point above the level of the wings is an inverted V-shaped brace frame 6, from the vertex of which guy wires 7 extend to the ends of the wings 3 and limit the downward movement of said wings to maintain the same in their normal position when the machine is at rest or not in flight. Guy wires 8 also 105 110

lead from the vertex of said brace frame to brace bars or beams 9 extending transversely above the surface 1 and connecting and reinforcing the upper edges of the surfaces 2, by which construction, in connection with front and rear sets of crossed stays 10, a very strong and rigid body structure is provided.

The upward motion of the wings 3 is limited or restricted by restraining means comprising cords or wires 11 and 12 provided at their outer ends with branches 11^a and 12^a leading to the respective wings, the inner ends of said cords extending beneath the surface 1 over suitable guide pulleys 13, and thence upwardly through an opening 14 in said surface, where they are connected with the forward end of a restraining spring 15 or its equivalent. The rear end of the spring is connected with a cord or wire 16 extending downwardly at the rear of the surface 1 over a guide pulley 17 and thence forwardly beneath said surface, said cord or wire being connected with the lower arm of a movable holding and tension regulating lever 18, said lever extending upwardly through an opening in the surface 2 and having its operating arm 19 disposed above said surface and provided with a pawl 20 to engage a rack 21, whereby the lever may be locked in any of its adjusted positions. A connection 22, including a contractile spring 23, connects the operating arm of the lever with a portion of the surface 2 in rear thereof, said connection acting in opposition to the pull of the restraining device when the lever is unlocked to prevent too forcible motion of the lever, as well as to decrease the amount of power required to adjust the lever for tensioning said restraining device.

It will be apparent from the foregoing description that the restraining device operates to yieldingly hold the flexible wings from upward motion and in normal minimum dihedral position, which holding action may be increased or diminished by tensioning or relaxing said restraining device and consequently rendering the wings stiffer or more flexible in action as occasion may require, according to the weight of the load and the velocity of the wind currents. It will, of course, be understood that under pressure each wing is adapted to yield upwardly, in which operation it expands the restraining spring and relaxes the connection between the same and the opposite wing, permitting the latter to automatically and simultaneously swing upward to a corresponding position. Under all ordinary conditions, even when the wind is light, it will, therefore, be apparent that the wings will vibrate or flutter vertically, setting up a beating and air confining and shedding action similar to that of the wings of a bird 65 whereby the lifting force of the wings is

increased and the resistance diminished, enabling the machine to be driven at higher speed.

If at any time when the machine is in flight a gust of air of any considerable force liable to disturb the equilibrium of the machine strikes the wing at one side of the machine, such wing will recede upwardly under the wind pressure and assume a different dihedral position against the resistance of the spring of the restraining device, which in its expansion will relax the connection leading to the opposite wing, permitting the latter to instantly recede upwardly to a position corresponding to that of the first-named wing. By this mode of operation the gust of air will be caused to spend its force on the wing against which it strikes, thus relieving the body of the machine from the air pressure, whereby the machine will be prevented from bodily tilting, while at the same time the wings will simply change their sustaining position and thereby maintain the equilibrium of the machine. If the cross current of air should be strong enough to shift the wing and also transmit a portion of its pressure to the body of the machine as a whole, thus causing the machine to tilt, the surfaces 2 will coöperate with the wings to restore the machine to its normal balanced position.

In practice, the surface 1 may form a support for the pilot's seat 24 and the driving motor (not shown), the former being arranged at the front and the latter at the rear of said surface or in any suitable positions. As a result, the machine will have an extremely low center of gravity as regards the relation of the load weight to the supporting wings, and by making the surface 2 a lifting surface any tendency of the load weight to disturb the lateral balance through a pendulum action will be overcome.

It will be obvious that the construction of the restraining means may be varied within the spirit and scope of the invention, and that in the balancing action of the wings the necessity of the wings moving in reverse directions for balancing control is avoided, since the character of the connection is such that the wings simply change their angle of incidence to corresponding degrees any movement of one wing being instantly imparted to and duplicated by the other wing, rendering it impossible for the wings to shift in such manner as to destroy the balance of the machine. A bird-like type of machine is accordingly produced which may be built as strongly as a biplane machine and will automatically preserve its balance in any wind not exceeding in velocity the speed of the machine, rendering it only necessary for the operator to preserve the longitudinal stability.

Having thus described my invention, I claim:—

1. A monoplane flying machine embodying a central supporting surface, dihedral-angled adjustable laterally extending supporting surfaces arranged at an elevation above and beyond the lateral extremities of said central supporting surface, dihedral-angled upright vanes connecting the lateral extremities of said central supporting surface with the inner extremities of said lateral supporting surfaces, and controlling means for permitting said laterally extending supporting surfaces to move to different dihedral positions under air pressure, said means operating upon the upward movement of one of said laterally extending supporting surfaces under air pressure to permit the other laterally extending supporting surface to automatically move upward to a corresponding dihedral position.

2. A monoplane flying machine embodying a central supporting surface, upright vanes extending from the lateral extremities of said surface, vertically adjustable laterally extending supporting surfaces projecting from the upper extremities of the vanes, and controlling means for permitting said laterally extending supporting surfaces to move to different dihedral positions under air pressure, said means operating upon the upward movement of one of said laterally extending supporting surfaces under air pressure to permit the other laterally extending supporting surface to automatically move upward to a corresponding dihedral position.

3. A flying machine embodying a central supporting surface, upright surfaces rising from said central supporting surfaces, vertically adjustable wings extending from said upright surfaces, and means for securing movement of both wings to correspondingly inclined positions under the excess pressure of air upon either wing.

4. A flying machine embodying a central supporting surface, upright surfaces rising from the central supporting surface, wings extending from said upright surfaces, and means for securing movement of both wings to correspondingly inclined positions under the excess pressure of air upon either wing.

5. A flying machine embodying a central supporting surface, dihedrally inclined upright surfaces rising from the central supporting surface, dihedrally inclined wings extending from said upright surfaces, and means for securing movement of both wings to correspondingly inclined positions under the excess pressure of air upon either wing.

6. A flying machine embodying wings vertically yieldable to different dihedral positions, and means for securing automatic adjustments of said wings in the same di-

rection and to corresponding dihedral positions upon the movement of either wing under air pressure.

7. A flying machine embodying wings pivoted for automatic upward yielding movement under air pressure from a normal position, a restraining device, and connections between the wings and restraining device, whereby when one wing moves upwardly under air pressure the connection between the restraining device and other wing will be relaxed to permit the latter-named wing to have a corresponding upward automatic movement under air pressure.

8. A flying machine embodying wings pivoted to move in a vertical plane, and means for permitting said wings to have yielding movement, said means being operative upon the automatic movement of one wing under air pressure in one direction to permit corresponding automatic motion of the other wing in the same direction.

9. A flying machine embodying wings pivoted to move automatically in a vertical plane under air pressure, an expandible restraining device, and connections between said restraining device and the wings, whereby when one wing moves upwardly under air pressure and expands the restraining device the connection with the other wing will be relaxed to permit of a corresponding movement of such wing under air pressure.

10. A flying machine embodying wings pivoted for vertical movement, a restraining device adapted to permit corresponding movements of the wings when either wing is forced upward under air pressure, and means for regulating the resistance of said restraining device.

11. A flying machine embodying wings pivoted for movement in a vertical plane, an expandible and contractible restraining device, connections between said restraining device and the wings, whereby upon the upward movement of one wing under air pressure the other wing will be permitted to have corresponding movement, and means for tensioning said restraining device.

12. A flying machine embodying wings pivoted for vertical movement, an expandible and contractible tensioning device, connections between said tensioning device and the wings, whereby upon the upward movement of one wing under air pressure the other wing will be permitted to have corresponding movement, a lever for tensioning said restraining device, and means for locking said lever in adjusted position.

13. A flying machine embodying a central supporting surface, upright surfaces rising from the central supporting surface, wings pivoted for vertical movement to said upright surfaces, and a restraining de-

vice, and connections between said restraining device and the wings, whereby upon the upward movement of either wing under air pressure the other wing will be permitted 5 to have corresponding movement.

14. A flying machine embodying a central supporting surface, upright surfaces rising from said central supporting surface, wings extending from said upright surfaces and 10 pivoted for vertical movement thereto, a restraining device, connections between the restraining device and the wings, whereby upon the upward movement of one wing the other wing will be permitted to have corresponding movement, and means for tensioning 15 said restraining device.

15. A flying machine embodying wings vertically adjustable to different positions, and controlling means operating to normally 20 resist upward movement of said wings, said means being operative to permit either wing to have upward movement under air pressure thereon, and to permit the other wing to move automatically upward to a corre- 25 sponding degree.

16. A flying machine embodying vertically movable wings, each wing being automatically movable upwardly under air pressure, and means operating upon the upward 30 movement of either wing to permit the other

wing to move upward to a corresponding degree.

17. A flying machine embodying vertically movable wings, each wing being automatically movable upwardly under air pressure, restraining and controlling means operating to permit upward movement of either wing under air pressure and to permit corresponding upward movement of the other wing, and means for regulating the restraining action of said restraining and controlling means. 35

18. A flying machine embodying vertically movable wings, a restraining device for maintaining the wings at a corresponding normal position, said restraining device being operative to permit either wing to move upward automatically under air pressure and to permit corresponding automatic upward movement of the other wing under 40 air pressure, and manually operable means for synchronously regulating the resistance of the restraining device to the movement of each wing. 45

In testimony whereof I affix my signature 50 in presence of two witnesses.
